UNITED STATES PATENT OFFICE.

CHARLES OSEAN, OF WOODCLIFF, NEW JERSEY, ASSIGNOR TO NATIONAL CARBON COMPANY, INC., A CORPORATION OF NEW YORK.

DESIGN FOR A FLASH LIGHT.

Application filed December 26, 1923. Serial No. 8,147. Term of patent 14 years.

To all whom it may concern:

Be it known that I, CHARLES OSEAN, a citizen of the United States, residing at Woodcliff, in the county of Hudson and State of New Jersey, have invented a new, original, and ornamental Design for Flash Lights, of which the following is a specification, reference being had to the accompanying drawing forming a part of this application, wherein—Fig. 1 is a side view, Fig. 2 is a front view and Fig. 3 is a top view of a flash light embodying the invention.

The cylindrical casing C has a bottom cap K coupled to one end and an elbow head

fitting E coupled to the other end. A switch S is mounted on the casing C, and a lens or cover glass G and a hanger H are mounted on the head E. The configuration and ornamentation of the flashlight casing assembly,—which includes the cylindrical portion C, the bottom cap K, and the elbow head E—constitute the dominant feature of my invention.

I claim:

The ornamental design for a flash light substantially as shown and described.

CHARLES OSEAN.
